UNITED STATES PATENT OFFICE.

SAMUEL D. ELDRED, OF MINONK, ILLINOIS.

CHECK-LIST FOR REGISTERING RAILWAY-PASSENGERS.

SPECIFICATION forming part of Letters Patent No. 297,588, dated April 29, 1884.

Application filed June 9, 1883. (No model.)

To all whom it may concern:

Be it known that I, SAMUEL D. ELDRED, of Minonk, Illinois, have invented a new and useful Improvement in Check-Lists for Registering Railway-Passengers, of which the following is a description, reference being made to the accompanying drawings for explanation and illustration.

My invention is to provide a check-list for registering the passengers in each car, their entrance, destination, and how passage is paid, and to enable the conductor to determine who has paid and who has not; and it consists in the car check-list shown in the drawings. Thus 15 in the drawings, which is only a part of a complete car-list, P L denotes the platform; W C, the closet; S, the stove; and 1, 2, 3, 4, 5, and 6 are so many seats in the car, each of which accommodates two passengers, all the seats in 20 the car being numbered in consecutive order from 1 to as many as there may be in a car. The check-list contains a full diagram of all the seats with their appropriate numbers, and in each seat are a number of figures and letters, 25 as shown in the drawings. The figures, from "1" to "20," indicate the station-numbers, and are arranged at each end of each seat; and the conductor punch-marks the figure to denote the station where the passenger is taken up 30 and the one to which he is going in the proper side of each. Thus in seat No. 1 a passenger enters at station No. 1, and takes a seat on the inner side of seat 1, and is going to station 6, and accordingly the conductor punches "1" 35 and "6" on that side row of figures in seat No.

1. If he pays by ticket, the conductor makes a punch-mark opposite "T," by half-ticket, opposite, " $\frac{1}{2}$ T;" cash, "C," one-half cash; " $\frac{1}{2}$ C," pass, "P;" mileage-ticket, "M;" coupon-ticket, "Co." The same characters appear 40 in every seat in the diagram. On excursions the aisle may be filled with figures opposite the seats to be used if needed. "240" is the number of the car. The other words—"Date," "Conductor," and "Trip No."—explain themselves, and are to be properly filled up by the conductor. Room is left for several punch-marks, so as to allow for different occupants of 45 the seats. When the conductor's run is completed, he passes the check-list in to the auditing officer and settles with him according to its requirements, and produces the vouchers and 50 money therefor.

What I claim, and desire to secure by Letters Patent, is as follows:

The check-list herein described, containing 55 a diagram of the interior arrangement of seats in a passenger-car, upon which the numbers of seats, station-numbers, and a series of letters indicating manner of payment of fare, are 60 all combined substantially as and for the purposes described.

In witness that I claim the invention set forth in this application I have hereto set my hand, at Indianapolis, Indiana, this 11th day 65 of April, 1883.

SAMUEL D. ELDRED.
